(57) **CLAIM**

The ornamental design for a bone shaped clamp as shown and described.

DESCRIPTION

FIG. 1 is a perspective view of a bone shaped clamp showing our new design in accordance with a first embodiment;

FIG. 2 is an exploded perspective view thereof;

FIG. 3 is an exploded perspective view thereof;

FIG. 4 is a top plan view thereof, the bottom plan view being identical to the top plan view;

FIG. 5 is a right-side elevational view thereof, the left-side elevational view being a mirror image of the right-side elevational view;

FIG. 6 is a back-side elevational view thereof, the front-side elevational view being identical thereto;

FIG. 7 is a perspective view of the bone shaped clamp in accordance with a second embodiment;

FIG. 8 is a bottom plan view thereof, the top plan view being identical to the bottom plan view; and,

FIG. 9 is a right-side elevation view thereof, the left-side elevational view being a mirror image of the right-side elevational view.

The dash-dash broken lines in the figures show portions of the bone shaped clamp that form no part of the claimed design. Dash-dot-dot-dash lines define the bounds of the claimed design and form no part thereof. The bone shaped clamp is shown with symbolic break lines in its length that are illustrated by dash-dot-dash lines. The appearance of any portion of the bone shaped clamp between the symbolic break lines forms no part of the claimed design. As indicated in the title, the article of manufacture to which the ornamental design has been applied is a clamp (e.g., pet treat/toy clamp).
